US0D1096047S

(12) **United States Design Patent** (10) **Patent No.:** **US D1,096,047 S**
(45) **Date of Patent:** **** Sep. 30, 2025**

(54) **WASTE RECEPTACLE**

(71) Applicant: **Zhejiang Erhui Technology Co., Ltd.**,
Taizhou (CN)

(72) Inventor: **Ting Zhou**, Taizhou (CN)

(**) Term: **15 Years**

(21) Appl. No.: **29/903,687**

(22) Filed: **Sep. 27, 2023**

(51) LOC (15) Cl. **09-09**

(52) U.S. Cl.

USPC **D34/7**

(58) **Field of Classification Search**

USPC D34/1, 5, 7, 8, 11; D32/37

CPC B65F 1/00; B65F 1/002; B65F 1/1426;

B65F 1/006; B65F 1/004; B65F 1/0033;

B65F 1/1638; Y10S 220/908

See application file for complete search history.

(57) **CLAIM**

The ornamental design for a waste receptacle, as shown and described.

DESCRIPTION

FIG. 1 is a perspective view of a waste receptacle, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom view thereof.

The broken lines in the drawings depict portions of the waste receptacle and form no part of the claimed design.

1 Claim, 7 Drawing Sheets
